SIGNAL CASING

Filed Nov. 23, 1928

INVENTOR

CHRISTIAN M. JACOBSEN

By Thomas L. Day
Attorney

UNITED STATES PATENT OFFICE

CHRISTIAN M. JACOBSEN, OF NEWCASTLE, INDIANA

SIGNAL CASING

Original application filed February 27, 1928, Serial No. 257,257. Divided and this application filed November 23, 1928. Serial No. 321,448.

This invention relates to improvements in casing-structures intended for the retention and shelter of the lamp parts and display plates and fittings of signal devices carried by automobiles, such signal devices comprising a multiple number of display or sign legends, and electric lamp devices for the illumination of same. In a casing structure of the class referred to it is essential that same may be weatherproof, strong and durable; and that the maximum efficiency of the lamps used may be obtained, and also that the interior of the casing may be accessible for the purpose of replacements or renewal of the interior parts.

The above desired advantages are obtained, and the objects of my invention are accomplished, by the new construction, combination and arrangement of parts illustrated in the accompanying drawings and described in the following specification. The invention is defined in the appended claims.

The several parts of my improved signal casing, as they appear in the different views in the drawings, are identified by suitable characters of reference. The casing is shown as embodied in form suitable to be attached to motor driven vehicles of all kinds, and it is of the specific form and arrangement adapted for the lamp parts and indicator plates forming part of the equipment described in my application Serial Number 257,257, filed February 27, 1928, and of which the present application is a division.

Figure 1 is a front view of my improved signal casing.

Figure 2 is a rear view of Figure 1.

Figure 3 is an enlarged frontal view of the structure as shown in Figure 1, portions of the sign display plate, and portions of the marginal securing members being broken away, disclosing to view the partition webs that constitute the several compartments in which the lamp bulbs are retained.

Figure 4 is a vertical cross section view taken on the line 4-4 and as viewed in the direction indicated by arrow 4 in Figure 3.

Figure 5 is a sectional plan view taken on line 5-5 in Figure 3.

Figure 6 is an enlarged cross section view

of the clamping and holding means, for uniting the display plate to the housing.

My invention contemplates the providing of a box-like housing having a flanged frontal opening, partitions in said housing to constitute compartments therein adapted for the retention of electric lighting devices, each of which said partitions extends to a plane substantially coincident with the plane of the face of the flanged opening, a gasket seated on the flange, a sign bearing plate to rest against the said gasket, and means to close said opening and to draw and hold the plate and gasket to removable coengagement with the said flange.

In the present embodiment of my invention and which provides for an upper compartment, a central compartment, lateral compartments, and two lower compartments, one above the other, the means for closing the opening and for drawing and holding the plate and gasket into the clamped coengagement with the flange of the housing, comprises a mask having webs to register with the faces of the said partitions and having its marginal portion to register with the marginal portion of the plate, a rim frame having a continuously extending shank to embrace the flange portion of the housing, and being provided with an inturned edge to engage the marginal portions of the said mask, and tightening connections between the shank of said rim frame and the exterior face of the flange of the housing.

The housing portion of my improved signal casing, is preferably made of pressed sheet metal fashioned in the general contour as shown in the drawings, the sides 1 and 2, the top 3, and the bottom 4, being formed integral with the back 5. The marginal portion of this box-like housing is provided with the continuously extending flange 6 of beveled formation in cross section, as shown in Figure 4, and which said flange has the frontal face 6^a and the rear face 6^b. An opening in the bottom 4 of the housing (see Figure 5) is formed by shearing on the lines 7 and 8, and it provides an outlet for the light afforded from the lowermost compartment. That portion of the metal between said lines

7 and 8 is bent downwardly, and it constitutes a plate 9, as shown in Figures 1, 2 and 4. This plate 9 is provided with spaced holes 10 and it constitutes a support for the usual license number plate P which is required to be illuminated. The said license plate may be secured by clamp bolts having the wing nuts 11.

By virtue of the foregoing construction and combination it is practicable to have the housing structure of the distinctive formation shown, the main portion being of width to provide for side-by-side signal designations, and the upper and lower portions being of lessened width. The compartments in the housing are constituted by light metal webs or partition plates 14, 15, 16 and 17. By this arrangement and construction there are provided the upper compartment, a central compartment, lateral compartments, a lower compartment, and a lowermost compartment, designations being delineated on the sign plate for said compartments, Turning, Parking, Right, Left, Stop, and Danger, respectively. By the peculiar arrangement as described, facility is afforded whereby the electric bulbs for the illumination of said compartments, may be so retained that the most effective display of the signal designations on the sign plate is possible.

For the retention of the sockets for the several lamp bulbs necessary for said illumination, clamp brackets 20 of the usual formation are secured to the inner face of the back plate 5, so that the sockets and bulbs, as shown by the dotted lines, may occupy the relative positions as shown plainly in Figure 3. A di-electric bushing 22 which is secured in a suitable opening therefor in the said back plate 5, affords proper insulation for the conductor cords (not shown) which are passed into the housing for connection to the lamp sockets. Secured to the rear face of the said back plate, is a sheet metal support arm 23 which is U shaped in cross section, and which shelters the opening in the back plate and the conductor cords which are passed therethrough, and which also constitutes a support for the said housing. The extended portions 23^a of the said support arm are connected to a foot block 24, by a swivel connection 25. By means of the wing nut 26, the sides 23^a of the support arm may be clamped securely to the foot block, after the position of the said block, and the position of the housing, have been adjusted. By this arrangement and combination of parts it is practicable to readily secure the signal casing in position in connection with surfaces of any angle. The foregoing structure is practicable of fabrication in sheet or cast metal, all interior surfaces being readily accessible for finishing, and for the reception of such parts as are to be disposed therein. The gasket 27, which is to be seated on the beveled face 6^a of the hous-

ing flange 6, may be made of rubber or like suitable waterproof composition, and is of the formation in cross section as shown in Figure 6. The beveled face 27^a of said gasket is adapted to rest directly against the said face 6^a of flange 6, and the heel 27^b is adapted to engage the interior edge of the said housing flange, thereby facilitating the disposal of the gasket in its correctly seated position on the said flange 6. Upon the frontal face 27^c and within the marginal rim 27^d of the said gasket, the marginal portions of the suitably formed translucent or transparent glass plate 28 are readily seated. By this arrangement there is the weather and dust proof uniting of the glass plate with the mouth or flange portion of the housing. Adapted to be disposed immediately in front of the said plate 28, is a mask member 30. This mask is made of relatively thin, stiff light sheet metal, and has its marginal portions of contour to register slightly beyond the edges of the glass plate 28. Web members 30^a formed integral with the marginal portion of the said mask are of such formation as to close from view the frontal edges of the partitions of the housing, and to define distinctly the areas in which the characters of the signals appear on plate 28. The mask so constructed and arranged constitute a shield for the protection of the glass plate, and its marginal portions constitute an abutment against which the interior edge of the rim frame, presently to be described, may have contact.

To unite the housing flange 6, the gasket 27, and the mask 30, I provide a rim frame 31. This rim frame is of contour to register with the marginal portion of the housing and is of hook shape in cross section, as shown in Figure 4. The inturned edge or lip 31^a engages the outer surface of mask 30. In the body portion or shank 31^b of this rim frame, and spaced as shown in Figures 1, 2 and 3 are cap screws 32. The location of these cap screws 32 is such, that their ends are adapted to engage directly the rear faces 6^b of the casement flange 6. The several parts after having been assembled in the manner just described, are readily drawn to secured status, by the turning of the screws 32, the effect of which tightening, is to draw the glass plate and gasket into tightly clamped and binding jointure with the flanged mouth of the casement. Thus the mouth opening of the housing is closed against the weather, and the plate and gasket are drawn and held in united but removable engagement with the said housing. For obtaining the maximum illuminating effect of the electric lamps, a solid white finish is applied to the interiors of the compartments in the housing. The width of the web portions 30^a of the mask are such as to prevent the passing of light from the slight space between the face of the partition and the glass plate 28, and to constitute a sharply

defined framing of the area of the plate upon which the signal characters are delineated. The said signal characters are preferably of white frosted effect making them of maximum distinctness on an opaque or semi-opaque field. The exterior surfaces of the housing, and of the mask may be finished by electroplating or by the application of weather proof enamels suitable for such purpose.

5 My invention is applicable for use for signal systems of types comprising equipment and circuits for a more or less number of signals. Whereas I have shown my improved 10 casing as adapted for a maximum number of compartments, namely six, I wish it to be understood that for requirements calling for a lesser number of compartments and signal delineations, modification is easily made by 15 simply the alteration of the positions of the partitions, and of the lamp bracket clamps, and of the web portion of the mask.

20 By obtaining the foregoing advantages, without the necessity of alteration or change 25 in the major details of construction, material saving in the providing of these improved signal casings for a wide variety of purposes, is effected. A signal casing constructed in accordance with my invention is suitable for 30 use at the rearward, as well as the forward portion of the automobile, or other vehicle for which it may be intended.

35 Whereas in the present specification I have shown and described the embodiment and details of construction preferred for carrying my invention into effect, I am aware that modifications may be made within the scope of the invention as same is defined in the appended claims, without departing from the 40 spirit of my invention or sacrificing any of its advantages.

What I claim as my invention, is:

1. A signal casing device, comprising a box like housing provided with a beveled marginal flange, partitions in said housing to constitute compartments therein, a weatherproof gasket seated on said beveled flange, and whose frontal face is provided with an interior shoulder, a sign bearing plate having its 45 edge portions to rest in engagement with the frontal face and anterior shoulder respectively, of the said gasket, a mask adapted to be disposed immediately in front of the sign bearing plate and having its edge portions to 50 register with the edge portions of said plate, a rim frame, hook shaped in cross section, the shank portions of which embrace the anterior edge of said flange and the lip portion being adapted to engage the frontal marginal portions of the said plate, and screws passed through the shank portions of the rim frame to engagement with the rear faces of the beveled flange of the housing, and which 55 screws when tightened cause the plate and gasket to be drawn and held in close fitting but removable engagement with the said flange.

2. A signal casing device, comprising a box like housing provided with a beveled marginal flange, a weatherproof gasket seated on

said beveled flange, and whose frontal face is provided with an anterior shoulder, a sign bearing plate having its edge portions to rest in engagement with the frontal face and anterior shoulder respectively, of the said gasket, 70 a mask adapted to be disposed immediately in front of the sign bearing plate and having its edge portions to register with the edge portions of the plate, a rim frame, hook shaped in cross section, the shank portions of which embrace the anterior edge of said flange, and connections between said rim frame and the housing to draw the rim frame to and to hold same in position whereby to hold the plate, the gasket and the mask in close fitting but 75 removable engagement with the said flange.

3. A signal device casing, comprising a housing having its walls of formation to provide a frontal opening, the edge portions thereof being flared at an oblique angle to 80 constitute a beveled flange, a gasket having a beveled rear face and an interior heel to engage the frontal face and the interior edge, respectively, of the said flange, and the frontal face of the gasket being provided with an anterior shoulder, a sign-bearing plate having its edge portions to rest in engagement with the frontal face and anterior shoulder, respectively, of the said gasket, a rim frame 85 hook-shaped in cross section and whose body portion is adapted to embrace the said beveled flange, and whose inturned lip is adapted to engage the frontal face of the said sign-bearing plates, and screws threaded through the said shank and adapted to impinge against 90 the rear face of said beveled flange.

4. A signal casing of the kind described, comprising a box-like housing provided with a beveled marginal flange, partitions in said housing to constitute compartments therein, a weatherproof gasket seated on said beveled flange, a translucent plate to rest against said gasket, a rim frame hook-shaped in cross section the shank portions of which embrace the anterior edge of said flange and the lip portion being adapted to engage the frontal marginal portions of the said plate, and screws passed through the shank portions of the rim frame to engagement with the rear faces of the beveled flange of the housing, and which 100 screws when tightened cause the plate and gasket to be drawn and held in close fitting but removable engagement with the said flange.
